UNITED STATES PATENT OFFICE.

DAVID CROWNFIELD, OF CAMBRIDGE, MASSACHUSETTS.

WALL OR CEILING FIXTURE FOR LIGHTS.

1,112,197.

Specification of Letters Patent. Patented Sept. 29, 1914.

Application filed March 6, 1914. Serial No. 822,817.

To all whom it may concern:

Be it known that I, DAVID CROWNFIELD, a citizen of the United States, and resident of Cambridge, in the county of Middlesex and State of Massachusetts, have invented new and useful Improvements in Wall or Ceiling Fixtures for Lights, of which the following is a specification.

My invention relates to fixtures for lights, and its object is to provide a fixture adapted for securing to a wall or ceiling or other part of a building and which shall be free from dust-collecting surfaces and angles so that the fixture may be peculiarly suited to hospitals.

The construction of my light fixture has for its chief characteristic freedom from any dust-collecting surfaces, and secondarily, simplicity of construction and ease of attachment and adjustment.

In the drawings hereto annexed which illustrate an example of my invention,—Figure 1 is a vertical section of the light fixture secured to a ceiling; Fig. 2 is a top plan view of a shade adapted to be attached to and form part of the fixture; Fig. 3 is a vertical section on an enlarged scale of parts of the hanger and shade holder, and the attachment for securing a lamp socket; Fig. 4 is a view in perspective of the shade holder; and Fig. 5 is a view in perspective of the top part of the shade.

In Fig. 1 the light fixture is shown as affixed to a ceiling and depending therefrom. It may, however, be affixed to such part of a building that it will not hang vertically. The nipple 2 forming part of a conduit for the introduction of the lighting medium to the lamp is secured to and depends a short distance from the ceiling 1. The leader pipe 3 is secured into the nipple 2 and is screw-threaded at its lower end for the attachment of the threaded sleeve 4. This sleeve is stepped and threaded on each of its portions 5, 6 and 7, these portions being of successively diminished diameters.

The hanger 8 is secured to the building through the medium of the leader pipe 3 by being screwed upon the thread at 5, so that the hanger constitutes a sleeve surrounding the leader pipe 3. Near the upper end of the hanger 8 there is secured or otherwise formed an enlargement 9, this enlargement being internally screw-threaded to receive and engage with the screw thread on the nut portion 11 of the canopy 10. This

canopy is shaped so as to embrace the hanger closely at one end, and to flare toward the ceiling or other portion of the building from which the hanger is suspended and is adjustably secured by means of the screw threaded connection between the parts 9 and 11. It will be observed that this connection is wholly interior to the canopy 10 so that the smooth exterior surface of the canopy is unbroken by the protrusion of any fastening means.

At the lower end of the hanger 8 there is secured the shade holder 12 which has a nut member 13 secured to it at or near its upper end, this nut member 13 being adapted to make threaded engagement with the threaded portion 6 on the sleeve 4. The shade holder 12 flares outwardly and downwardly, its upper end being of substantially the same diameter as the hanger 8, so that when the upper end of the shade holder 12 is abutted against the lower end of the hanger 8, the outer surfaces of these two members shall be substantially continuous and without any ledge, seam or other break in the surface. The reduced diameter of the threaded portion 6 of the sleeve 4 allows the shade holder 12 and hanger 8 to abut, with substantial continuity of surface, without any ledge or projection.

A lamp socket 14 is secured by a screw-threaded connection through the smallest threaded portion 7 of the sleeve 4, the socket and the threaded portion being entirely housed inside the shade holder 12. The means for securing the shade 17 to the bell-shaped holder 12 are interior to the said shade holder and consists in the example shown of the inturned spurs 16 which are so spaced around the periphery of the bell-mouth on the shade holder that they will enter corresponding notches 19 in the top flange of the shade 17. This top flange 18, which is preferably integral with the body 17 of the shade, is connected to the main body of the shade by webs 20, each of which is intermediate between adjacent notches 19.

To attach the lamp fixture, the leader pipe 3 is secured into the nipple 2, with the hanger 8 screwed to the sleeve 4, and the sleeve 4 screwed to the lower end of the leader pipe 3. The canopy 10 is then slipped over the hanger 8 and slid along until the nut member 11 can be engaged with the corresponding thread of the enlargement 9 and then the canopy 10 is adjusted toward the

ceiling 1 until it comes into close contact therewith. The lower and smaller end of the canopy 10 should fit closely around the hanger 8. The shade holder 12 is then secured to the sleeve 4 by screwing its nut portion 13 over the threaded portion 6 of the sleeve 4. The lamp socket 14 may then be screwed over the threaded part 7 of the sleeve 4 and the shade 17 then attached to the shade holder 12 by passing the flange 18 into the mouth of the shade holder so that the notches 19 will pass over the spurs 16 of the shade holder. The shade 17 is then given a slight turn so that the spurs 16 will engage with the under side of the flange 18 on the shade. The means of securing the shade to the shade holder are wholly interior to the shade holder, and all of the fastening devices involved in the construction of the above described light fixture are interior to and concealed by the members which constitute the outer shell, namely, the canopy 10, hanger 8 and shade holder 12. The external surfaces of these members are smooth and unbroken, and form no dust-collecting ledges, so that a minimum of dust can collect upon the fixture and the fixture as a whole is very easily wiped clean whenever desired.

30 I claim:

1. In a light fixture, the combination of a tubular hanger, means to secure the hanger to part of a building, a canopy surrounding the hanger, adjustable means wholly interior to the canopy, securing the same to the hanger, a shade holder secured to the free end of the hanger, means wholly interior to the shade holder to secure a shade thereto, and means to attach a light to the hanger on the inside of the shade holder.

2. In a light fixture, the combination of a tubular hanger, means to secure the hanger to part of a building, a hollow outwardly flaring canopy surrounding the hanger, the hanger and canopy in screw thread connection inside the canopy, a shade holder secured to the free end of the hanger, means wholly interior to the shade holder to secure a shade thereto, said shade holder overhanging said shade fastening means, and means to attach a light on the inside of the shade holder.

3. In a light fixture, the combination of a tubular hanger, means to secure the hanger to part of a building, an enlargement near one end of the hanger, a hollow outwardly flaring canopy embracing the hanger at its smaller end and provided with internal means to engage the enlargement on the hanger adjustably, a sleeve secured to the free end of the hanger internally of the same, said sleeve provided with a section of smaller diameter than that secured to the hanger, a shade holder secured internally to said smaller sleeve section, means wholly

interior to the shade holder to secure a shade thereto, said shade holder overhanging said shade fastening means, and means to attach a light to the shade on the inside of said shade holder.

4. In a light fixture, the combination of a tubular hanger having an enlargement, means to secure said hanger to part of a building, a canopy having an opening for said hanger and a screw threaded portion 75 adapted to coöperate with said enlargement adjustably to secure said hanger and said canopy, a threaded sleeve on said hanger, a shade holder secured to said sleeve and abutting against said hanger whereby the outer 80 surface of said holder and hanger are substantially continuous, means wholly interior to the shade holder to secure a shade thereto, and means to attach a light on the inside of said shade holder.

5. In a light fixture, the combination of a tubular hanger, means to secure the hanger to part of a building, a hollow canopy surrounding the hanger, adjustable means 90 wholly interior to the canopy securing the same to the hanger, a sleeve secured on the free end of said hanger internally of the same, said sleeve provided with a section of smaller diameter than that secured to the hanger, a shade holder having an interior 95 screw threaded portion secured to said smaller sleeve section and provided with internal spurs spaced apart for securing a shade, and means to attach a light on the inside of said shade holder.

6. In a light fixture, the combination of a tubular hanger, means to secure the hanger to part of a building, a hollow canopy surrounding the hanger, adjustable means wholly interior to the canopy securing the same to the hanger, a sleeve secured on the free end of said hanger internally of the same, said sleeve provided with a section of smaller diameter than that secured to the hanger, a shade holder having an interior 105 screw threaded portion secured to said smaller sleeve section and provided upon the periphery of its mouth with inturned spurs spaced apart, a shade having a flange provided with notches adapted to coöperate 110 with said spurs to secure said shade to said shade holder, and means to attach a light on the inside of said shade holder.

7. In a light fixture, the combination of a tubular hanger having an enlargement, 120 means to secure said hanger to part of a building, a hollow outwardly flaring canopy embracing the hanger and having a screw threaded portion adapted to coöperate with said enlargement adjustably to secure said 125 hanger and said canopy, a threaded sleeve secured to the free end of the hanger internally of the same, said sleeve provided with a section of smaller diameter than that secured to the hanger, a shade holder having 130

an interior screw threaded portion secured to said smaller sleeve section and abutting against said hanger whereby the outer surface of said holder and hanger are substantially continuous, means wholly interior to the shade holder to secure a shade thereto, said shade holder overhanging said shade fastening means, and means to attach a light to said sleeve on the inside of said shade holder.

8. In a light fixture, the combination of a tubular hanger having an enlargement, means to secure said hanger to part of a building, a hollow outwardly flaring canopy embracing the hanger and having a screw threaded portion adapted to coöperate with said enlargement adjustably to secure said hanger and said canopy, a threaded sleeve secured to the free end of the hanger in-

ternally of the same, said sleeve provided with a section of smaller diameter than that secured to the hanger, a shade holder having an interior screw threaded portion secured to said smaller sleeve section and abutting against said hanger whereby the outer surface of said holder and hanger are substantially continuous, a shade having a flange provided with notches adapted to coöperate with inturned spurs on said shade holder to secure said shade to said holder, and means to attach a light to said sleeve on the inside of said shade holder.

Signed by me at Boston, Massachusetts, this 27th day of February, 1914.

DAVID CROWNFIELD.
